GAS COCK

Casper S. Stuckenholz and John J. Slavin, Cleveland, Ohio, assignors to The W. J. Schoenberger Company, Cleveland, Ohio, a corporation of Ohio

Application September 9, 1936, Serial No. 100,011

1 Claim. (Cl. 251—165)

Our invention relates to improvements in gas cocks.

The object of our invention is to provide a cock of this character which can not be accidentally opened to allow the gas to flow to the burners and pertains particularly to the type of cocks in which the operating stem of the plug valve has a longitudinal movement for releasing it from its locked position, so that the plug valve can be then rotated to different positions.

Another object of the invention is to provide a cock of this type in which the operating stem and the spring controlling the latching members are retained in their relative assembled position within the turning plug, so that the same can be readily removed from the housing without affecting their assembled operative relation.

A further object of our invention is to provide a valve of this character in which the turning plug can be readily removed or inserted in the housing and in which all parts, during assembly operations, will automatically assume their proper position to allow the plug to be properly clamped in operative position.

A still further object of our invention is to provide a simple cheap and effective valve of this type having certain details of structure and combination of parts hereinafter more fully set forth.

In the accompanying drawing:

Figure 1 is a vertical sectional view of our improved valve;

Figure 2 is a top plan view partly in section showing locking nut removed;

Figure 3 is a vertical section view of the plug valve taken on the line 3—3;

Figure 4 is a perspective view of the plug and locking sleeve in their separated relation; and

Figure 5 is a side view of the plug valve showing a modified means of locking the stem in the plug valve.

Referring now to the drawing 1 represents the valve housing of the usual cast form having in one side an inlet 2 and in the opposite side an outlet 3 both communicating with the central tapering plug valve opening 4 which has its lower end closed by the solid wall 5. This wall is provided with an opening 50, closed by a screw plug 6, whereby the plug valve may be more readily removed from its opening in the event it should become corroded or otherwise wedged in the opening. The housing 1 is provided with an upwardly extending flange 7 into which extends the tapering valve opening and is externally threaded as indicated at 8 and upon which is screwed the nut 9 for holding a valve plug 10 in

position as will be hereinafter more fully described.

The plug valve 10 has its lower end 11 of the usual solid form and formed with an opening 12 therethrough and adapted to register with the oppositely arranged inlet and outlet openings 2 and 3. The upper end of plug valve 10 has a circular opening 13 extending from its upper end a considerable distance therein for the purpose of securing the operating stem, as will be presently described. The exterior of the valve plug has its upper end externally reduced as indicated at 14 and said reduced portion has a vertical or longitudinal slot 15 which communicates with the opening 13.

Within the opening 13 is the valve stem 16 which has its lower end 18 of a circular form to closely fit the opening 13 and is provided with a pin 17 extending outwardly through the slot 15 beyond the wall of the reduced portion 14 of the plug. The extreme lower end of the stem is provided with a circular depression 51 in which is arranged a coil spring 19 which engages the bottom thereof and normally exerts upward pressure on the stem. The valve stem 16 is slightly reduced from the point 20 to its upper end forming a shoulder at the point 20. The interior of the opening 13, in the plug, is provided with a semi-circular groove 21 which extends circumferentially around the plug from the walls of the slot 15, and fitting in said groove is a locking spring 21 which has outwardly turned ends 22 and 23 extending into the slot 15. This spring 21 engages the shoulder 20 of the stem 16 and limits the upward movement of the stem caused by the pressure of the spring 19.

The upper end of the flange 7, in opposite sides thereof, is provided with the notches 24 and 25 which are of different sizes for a purpose later described. The locking sleeve 26 is of a thickness 40 equal to the reduced portion of the valve plug so that it is free to pass over the same within the space formed thereby, between it and the flange 7 of the housing. The upper end of the sleeve on opposite sides is provided with lugs 27 and 28 of different sizes, corresponding in width with the notches 24 and 25 in which the lugs are adapted to seat. The sleeve is thus held in the housing against rotation and due to the relative sizes of the slots and lugs can only be placed therein in 50 one position, so that the locking feature can only have one position relative to the plug and its opening.

The locking sleeve at its lower end is formed with a cut away portion as indicated at 29, which 55

extends approximately one third of the circumference of the sleeve, and at one end of said cut away portion, is a notch 30 communicating therewith, and the pin 17 is free to move in the 5 cut away portion of the sleeve and enter the notches. Surrounding the valve stem is a nut 31 which has a portion 32 engaging the flange 1 and having an outwardly enlarged portion 33 internally threaded and screwed upon the 10 threaded portion of the flange 1 whereby the parts are locked in their operative position.

When the valve is closed the pin 17 has been forced by the spring 19 into the notch 30 and the plug can not be turned by the valve stem. When 15 in this position the valve is locked against turning movement. In order to open the valve the stem 16 is forced inwardly against the tension of the spring 19 and the pin 17 is moved downward out of the notch 30 into the cut away portion 29 of the sleeve and thus the valve by a 20 turning action of the stem is rotated to an open position, the pin traveling in said cut away portion until it reaches the end thereof, when the rotation of the plug is stopped and the valve is 25 in a wide open position. When in this position, and at all times, the spring 19 is forcing the valve stem upwardly and causing a frictional engagement of the pin 17 with the wall of the cut away portion of the sleeve and thus preventing the 30 easy turning of the plug. At the same time the spring is exerting a downward pressure on the plug to hold it tightly in the tapered opening.

In order to remove the stem from the plug, the two ends 22 and 23 of the spring 21, extending 35 into the slot, are forced together, thus withdrawing the spring from the groove 21' and allowing the stem and spring 21 to move outward from the opening 13 in the plug. This allows a new spring to be inserted at any time. In 40 assembling the stem and valve plug the spring 19 is first inserted in the plug and the stem pushed therein, the pin 17 traveling downwardly in the slot 15. The spring 21 is then slipped over the stem and the ends are then brought together, so that the spring can be forced downward between the stem and the inner wall of the opening 45 in the plug with the turned ends in the slot.

This downward movement is continued until the spring 21 is forced downwardly until it snaps into the groove 21'.

From the foregoing it will be seen that the 5 plug valve 10 and its stem 16, together with the coil spring 19 can be removed as a unit whenever it becomes necessary to grease the plug, as is frequently the case. Heretofore, this operation has proven particularly troublesome due to the fact that the spring 19 would frequently 10 become lost. Furthermore considerable difficulty was encountered in assembling these parts after the greasing operation.

In the modification shown in Figure 5 the 15 exterior of the upper end of the plug is provided with a groove 34 in which a contracting locking spring 35 is sprung and the spring engaging the pin 17 of the stem forms a stop to limit the upward movement thereof.

Having thus described our invention, what we 20 claim is:

A valve comprising a housing, a valve plug 25 therein having a reduced hollow extension, said extension formed with a circular recess and a longitudinal slot, a valve stem extending snugly into said hollow extension and longitudinally movable therein, a coil spring at the bottom of said hollow extension for holding said stem in extended position, a pin carried by the stem and extending through said longitudinal slot for locking 30 the stem against rotation in the plug and locking the plug against rotation in the housing in its closed position, said stem above said pin having a reduced portion to provide a shoulder on said stem and an annular space of substantial 35 width between said reduced portion and the valve plug, and an expansible split ring insertable through said space for engagement in said circular recess and engageable by said shoulder for preventing the stem from passing from the plug 40 when removed from the housing, said split ring being formed with bent ends extending into said longitudinal slot to facilitate assembly and disassembly of said ring.
